**PIVOT-BEARING ASSEMBLIES FOR WINDOWS
AND SIMILAR STRUCTURES**

Gunnar Erik Werner Lewin, Viggbyholm, Sweden, assignor to AB Atvidabergs Inredningar, Atvidaberg, Sweden, a joint-stock company of Sweden

Filed Jan. 21, 1964, Ser. No. 339,197

Claims priority, application Sweden, Jan. 22, 1963, 684/63

6 Claims. (Cl. 16—164)

This invention relates to pivot-bearing assemblies for pivot-windows and similar structures, adapted to be swung through an angle of about 180°.

It is an object of the invention to provide pivot-bearing assemblies for the purpose described having two parallel pivots adapted to support alternatively the window-sash or other pivoted structure when the latter is swung through an angle of about 180°, without the unbalanced weight of the structure becoming very great in any angular position. It is, therefore, a further object of the invention to provide pivot-bearing assemblies having their pivots closely spaced.

It is another object of the invention to provide a pivot-bearing assembly which affords easy control of the amount of friction between the pivots and the pivot-bearings.

It is a still further object of the invention to provide a pivot-bearing assembly with an adjustable fixing of one pivot, to compensate for any dimensional changes of the supported structure in its relation to the surrounding stationary structure, such as caused by settling, swelling, or the like.

It is a still further object of the invention to provide a pivot-bearing assembly which will permit an easy mounting and dismounting of a window-sash or like pivoted structure.

With these and other objects in view, the pivot-bearing assembly according to the invention comprises two parallel pivots, the first of which is stationary by being rigidly secured to the window-frame, or the like, whereas the second pivot is detachably secured to the window-sash, or the like, said pivots being formed as circular, comparatively thick discs rotatably disposed relative to a common housing, said discs being each shaped with a preferably arcuate recess, the radial depth of which is less than the distance between the disc centres, said discs overlapping so that the circumference of the first disc upon its rotation through an angle of, say, 90° will engage the recess of the second disc to prevent rotation thereof until the recesses of both discs have become juxtaposed, in which position abutting means will arrest rotation of said first disc, whereupon the circumference of said second disc will engage the recess of the first disc and prevent the rotation of the latter at the same time as the second disc will be freely rotatable.

With this arrangement any pivoting movement about the second pivot is altogether impossible during the rotation of the window-sash about the stationary pivot through an angle of about 90°. When the rotation through 90° is completed, the recesses of the pivot discs have become juxtaposed, and for the continued rotation the locking action will now be shifted over from the second disc to the first one.

An embodiment of the invention will now be described by way of example with reference to the drawings, in which

FIG. 1 is a diagrammatical side elevation view of a pivot-bearing assembly for a pivot window with the parts assuming the position in which the window is shut,

FIG. 2 is a similar view as FIG. 1 when the window-sash has been opened about 30°,

2

FIG. 3 is a similar view as FIG. 1 when the window-sash has been opened about 90°.

FIG. 4 is a similar view as FIG. 1 when the window-sash has been rotated through about 180°.

FIG. 5 is a sectional view along V—V in FIG. 1,

FIG. 6 is a sectional view along VI—VI in FIG. 4, and

FIG. 7 is a sectional view along VII—VII in FIG. 1.

In the drawings the window-frame and the window-sash have not been specifically illustrated, but their possible shapes and dispositions will be obvious to anyone skilled in the art.

For each window-installation, it will as a rule be necessary to provide two pivot-bearing assemblies, one at each lateral window-frame member. For the sake of simplicity, only one assembly will be described, however, as the shape and arrangement of the other assembly will become self-evident.

With particular reference to FIG. 5, a pivot-bearing assembly comprises a housing 3, two partially overlapping discs 6, 7 rotatably disposed within circular bores 4, 5, respectively, in the housing 3, a bracket 1 rigidly secured to the first disc 6, and another bracket 2 which is attached separably to the second disc 7 in a manner preventing any torsional displacement between said elements.

Bracket 1 will preferably be attached to a window-frame or the like by means of screws, whereas bracket 2 will be screwed onto a window-sash or the like.

The housing 3, preferably made of a light alloy, is formed with two bores 4, 5 which are sunk in the housing from opposite faces thereof and which each have a bottom. The bores have circular cross-section and a diameter and depth which corresponds substantially to the diameter and the thickness of the discs 6, 7, and they intersect somewhat. The bottom of each bore 4, 5 is pierced by a central bore for a central stud member passing through the corresponding disc, said stud members each shaped with a head abutting the outer wall of the housing 3. The first stud member 9 (FIG. 5) extends beyond the opposite face of disc 6 and is threaded. It may be secured with a nut and a locking washer to the bracket 1, to clamp the disc 6 rigidly against the latter. The second stud member 12 (FIG. 1) is adapted to journal rotatably the disc 7 in the bore 5 by means of a stationary, internally threaded bush (not illustrated).

Both discs 6, 7 are formed with a radially extending open split, and coinciding with each slit and between the ends thereof an axially extending bore 20 with opposed frusto-conical portions is provided. This bore receives expanding means 13, 14, respectively, preferably comprising a conical screw and a conical nut (FIG. 6) which may be tightened or loosened to expand or narrow the slit, thus varying the friction between the circumference of each disc and the corresponding wall of each bore 4, 5, making it possible to set the discs 6, 7 in any angular position independently of the position of the gravity axis of the window-sash.

Each disc 6, 7 is formed at its circumference with a substantially arc-shaped recess 15, 16. These recesses preferably extend only over so great a portion of the width of the discs as corresponds to the length of the common portions of the bores 4, 5. As thus the circumference of one disc may engage the recess of the other, the discs may overlap with an amount corresponding to the radial depth of the recess.

When the recess of one disc faces the intersection of the bores 4, 5, and the circumference of the other disc engages said recess, the first-mentioned disc is prevented from turning, whereas the other disc may be freely rotated.

The disc 6 which is rigidly clamped to bracket 1 is formed in the face thereof adjacent the bottom of bore 4 with an arcuate slot 18, in which a stud member 17

projecting from the bottom of the bore engages to form a pin-and-slot connection. When disc 6 has been rotated through a predetermined angle, its further rotation is arrested by one end of slot 18 abutting the stud 17. In that position, the recess 15 faces the intersection of bores 4, 5, that is the recesses 15, 16 of both disc 6, 7 are juxtaposed. In that position, the second disc 7 may begin to be rotated so that its outer circumference engages the recess 15 of the first disc 6 and locks the latter against rotation, whereas the other disc 7 has now become freely rotatable.

The central stud 9 passing through disc 6 may be formed with opposed flats or may have a square cross-section or the like, passing through an arcuate slot 8 in the bracket 1 to form a torsionally rigid connection. Alternatively, the disc may be formed with a square projection at that face, engaging the said arcuate slot. After loosening the nut (FIG. 5), the centre of disc 6 may be slid along the arcuate slot, thus to compensate for any change in the window structure, caused by dimensional variations, such as settling, swelling, or the like.

The disc 7 which is rigidly attached to bracket 2 is formed at the surface adjacent said bracket with a diametrically extending slot 10, preferably with a T-shaped cross-section. This T-slot 10 is adapted to receive a bar 11 with a corresponding cross-section, rigidly secured to bracket 2. When the later is swung in unison with the window-sash, disc 7 consequently is brought along in this movement. To make it possible to insert the bar 11 in the slot 10 a slot with a corresponding cross-section (not illustrated) is formed in the wall of the housing 3. The slots are preferably disposed and arranged in such a way that the window-sash, when swung 180°, may be lifted out of the bearings, the slots being aligned in that position. No special loosening measures have thus to be taken. The window-sash is mounted in its position in an analogous manner.

To make it possible to adjust the frictional engagement between the discs 6, 7 and the surrounding bores 4, 5 without dismantling any parts, bores 19 (FIGS. 1, 2 and 3) may be provided through the bottom of each bore 4, 5 at the same radial distance from the centre as the bores 20 in the discs. When a bore 19 is brought to coincide with a bore 20, the expanding means 13, 14 will become accessible to a suitable adjustment tool.

What I claim is:

1. For a pivot-window structure wherein a window-sash may be swung through 180°, the provision of at least one pivot-bearing assembly comprising two parallel pivots, one of which has a stationary axis and is rigidly attached to bracket means adapted to be secured to the stationary structure, such as a window-frame, whereas the second pivot is rigidly connected to bracket means adapted to be rigidly secured to the pivoted structure, such as a window-sash, said pivots comprising a housing and comparatively thick circular disc members rotatable therein, said disc members spaced at a center distance less than the sum of their radii, there being a substantially arcuate recess at the circumference of each disc member to enable the first disc member to engage the recess of the second disc member during the rotation of said first disc member through a desired angle, and thus to prevent the second disc member from rotating until the recessed portions of both disc members face each other, means being provided for arresting the rotation of the first disc member upon attaining said position, and thus to permit the outer circumference of said second disc member to engage the recess of the first disc member to immobilize the latter, at the same time as the second disc member becomes freely rotatable.

2. A pivot-bearing assembly as claimed in claim 1, wherein there are two partly intersecting circular sack bores in said housing for rotatably receiving said disc members, said bores facing in opposite directions and having a diameter substantially the same as the diameter of

said disc members, for frictionally engaging by their circumference the peripheral walls of said bores.

3. A pivot-bearing assembly as claimed in claim 1, wherein there are two partly intersecting circular sack bores in said housing for rotatably receiving said disc members, said bores facing in opposite directions and having substantially the same diameter as said disc members, the latter having each a radially extending open slit, there being an axially disposed through bore with opposed conical portions coinciding with said slit, and adjustable expansion means engaging said bore for widening and narrowing the slit to make said disc member engage the circumferential wall of said bore with a desired amount of friction.

4. For a pivot-window structure wherein a window-sash may be swung through 180°, the provision of at least one pivot assembly comprising two pivots with parallel axes, said pivots each formed as a comparatively thick circular pivot disc, means for rigidly attaching the first one of said pivot discs to a stationary window structure, such as a window-frame, means for rigidly securing the second pivot disc to a pivoted structure, such as a window-sash, there being an arcuate recess in the circumference of each pivot disc, a housing having two partly intersecting, oppositely facing parallel sack bores therein, each one adapted to receive rotatably one of said pivot discs with the recess of one disc normally engaging an edge portion of the other disc, means for adjusting the frictional resistance between the circumference of said pivot discs and the surrounding walls of said sack bores, means for limiting the pivoting movement of said housing relative to said first pivot disc, said means comprising a pin-and-slot connection between the said first pivot disc and the bottom of the surrounding bore, and a diametrically extending T-slot and T-stud connection between said second pivot disc and said means for rigidly securing the second pivot disc to a pivoted structure, such as a window-sash.

5. For a pivot-window structure wherein the pivoted window-sash may be swung through 180°, the provision of at least one pivot-bearing assembly comprising two pivots with parallel axes, said pivots each formed of a comparatively thick, circular-shaped disc, a first bracket member for rigidly securing the first one of said discs to a stationary structure, such as a window-frame, a second bracket member adapted for rigidly securing the second disc to a pivoted structure, such as a window-sash, there being an arcuate recess at the circumference of each disc over at least part of its width, a housing having therein two partly intersecting, oppositely facing axially staggered sack bores with substantially the same diameter as the discs, each bore adapted to receive rotatably one of said discs with the recess of at least one disc engaging an edge portion of the other disc, in each disc an open radially extending slit, there being an axially extending bore with opposed frusto-conical portions coinciding with each of said slits between the ends thereof, frusto-conical threaded means adapted to engage said bores for varying the width of the slit to attain a desired degree of frictional resistance between the circumferences of said sack bore and the corresponding disc, a pin-and-slot connection between the said first disc and the bottom of its surrounding bore to limit the pivoting movement of said housing relative to said first disc, a central stud member extending through a corresponding central bore in said first disc for clamping the latter to said first bracket member, there being an arcuate slot through said first bracket member adapted to adjustably receive the end of said stud member for varying the position of said first disc relative to the second disc, and a diametrically extending torsionally rigid T-slot and T-stud connection between said second disc and said second bracket member adapted to be attached to a pivoted structure, such as a window-sash.

6. In a pivot-bearing assembly as claimed in claim 5, there being the provision of a hole through the bottom of each of the said sack bores at the same radius as the axial bore coinciding with the radially extending slit in the disc received in each bore, to make possible the adjustment of the width of the slits without dismounting parts.
